X-RAY TUBESTAND

Edward A. Labus, Milwaukee, and Robert J. Mueller, Brookfield, Wis., assignors to General Electric Company, a corporation of New York

Filed Sept. 12, 1963, Ser. No. 308,405

7 Claims. (Cl. 250—91)

This invention relates to a tubestand for positioning an X-ray tube with respect to an X-ray table.

Among the objects of the invention are to provide an X-ray tubestand that is supported on the room structure independently of the X-ray table and away from it so that the operator may move around the table without interference by the stand.

Another object is to remove the lower guide track of such a tubestand from its customary position immediately adjacent the X-ray table, where the operator frequently tripped over it.

Another object is to support the X-ray tube on a telescoping extensible and contractible arm that facilitates transverse movement of the tube over the active width of the X-ray table and which permits the tube to be placed in a parked position where it does not interfere with activity around the table. An adjunct of this object is to provide a laterally telescoping tube support arm whose sections are adapted to move equidistantly and in unison for improved simplicity, appearance and sturdiness as compared with other telescoping supports of the prior art in which one section moved to its limit before the next section began to move. Other important features of the instant telescoping support are that its sections may be locked by locking only one section, and that it is readily adaptable of being motorized.

A further object of this invention is to provide a tubestand that facilitates directing the X-ray beam laterally and frontally through the patient, while the X-ray table is horizontal or angulated vertically, without the requirement of swinging the tube support arm parallel to the table as is necessary in prior designs. An incident to this feature is that the lower guide track for the longitudinally translatable upright member of the stand need only approximate the length of the X-ray table since the column does not have to go way beyond the table in order to direct the beam laterally through the patient's upper or lower extremities.

A further object is to provide a tubestand that has a small wheel base and takes up less floor space, this being facilitated in part by use of criss-cross cables to stabilize the upright member when it is at rest and in motion.

Yet another object is to provide a support that allows an X-ray tube to be positioned above or below the X-ray table top.

Achievement of these and other more specific objects will appear from time to time throughout the course of the specification.

A more detailed description of a preferred embodiment of the invention will now be set forth in conjunction with the drawings in which:

FIGURE 1 is a perspective view of the new tubestand installation accompanied by an X-ray table body which is shown in outline;

FIGURE 2 is a sectional view of the new telescoping tube support arm taken normal to a vertical plane whose edge may be viewed in the direction of the arrows 2—2 in FIGURE 1;

FIGURE 3 is a side view of the telescoping tube support arm which is partly in section as taken on the line 3—3 in FIGURE 2, some parts being omitted;

FIGURE 4 is a schematic representation of the vertical

2

tubestand column and the criss-cross stabilizing cables therefor;

FIGURE 5 is a schematic showing of the counter-balancing means for the X-ray tube support; and

FIGURE 6 shows the details of the lower guide rollers and track as viewed in the direction of the arrows 6—6 in FIGURE 5.

Referring to FIGURE 1, the tubestand comprises an upright member 9 including a pair of vertical columns 10 and 11 which extend between the upper guide rail assembly 12 and a lower guide rail assembly 13. The upright member 9 has wheels at its upper and lower extremities which cooperate with the guide rails in such manner as to allow the upright to be translated therealong unitarily and in parallelism with the wall of the room and an X-ray table 14. The wheels are typified by a showing of the lower wheels and track in FIGURE 6.

A carriage 15 that is adapted for vertical movement on columns 10, 11 has extending from its front an extensible and contractible X-ray tube support arm assembly that is designated generally by reference numeral 16. At the end of arm 16 the X-ray tube casing 17 is supported in such manner that it may be turned on the axis of the arm 16 and on its own longitudinal axis, thus enabling the X-ray beam to be directed downwardly toward the table top or laterally and longitudinally of X-ray table 14. Attached to the bottom of X-ray tube casing 17 is a beam defining cone or collimator assembly 18 which may be conventional.

In FIGURE 1, collimator 18 is disposed to direct the beam of X-rays in a vertical direction toward the top of X-ray table 14. It will be understood that X-ray table 14 is typically adapted to be angulated to either vertical position in which case the tube casing 17 would be rotated on the axis of arm 16 in an appropriate direction for aiming the X-ray beam so that it would penetrate the table top and record an X-ray image on a film which is usually in a cassette inside the table.

Occasions arise when the radiologist desires to take a lateral radiograph of a patient who is lying on the table top while the table is in an essentially horizontal position or while the patient is upright as a result of tilting the table to one of its vertical positions. In such instances, the X-ray tube casing 17 is rotated 90 degrees more or less so that the beam emerges out of bottom of the collimator which is to its left side as it appears in FIGURE 3. To permit rotation of the X-ray tube casing, it is journaled on four equiangularly spaced bearing pads 19 in an apertured bracket 20. When the casing is rotated to the desired position on its longitudinal axis, it may be clamped by actuation of a handle 21 whose associated mechanism is not shown in detail because it can be readily devised by a skilled mechanical designer. In FIGURE 3, it may also be seen that the X-ray tube casing is adapted for being rotated on the longitudinal axis of the telescoping arm assembly 16. This involves making a shaft and bearing connection between bracket 20 and the innermost section 25 of telescoping arm 16. The shaft and bearing are not shown but it may be seen that the bracket 20 and section 25 abut each other through the agency of circular bearing plates 22 and 23 which may be clamped and unclamped by actuation of a cam operating lever 24.

In FIGURE 1, the conventional electric power cables extending from the X-ray tube casing 17 to the power supply enclosure 26 have been omitted for the sake of clarity. The means for draping and handling the cables have also been omitted. The cable is admitted to the casing 17 via a socket 53, see FIGURE 3.

The telescoping X-ray tube support arm assembly 16 will now be described primarily in connection with FIGURES 2 and 3. The arm assembly 16 extends from the

vertically movable carriage 15. The carriage is mounted on tracks that are on the back of columns 10, 11 but these and their rollers are not shown since they are a matter of designers choice. In FIGURE 3 it will be observed that, in this example, the telescoping arm assembly 16 comprises four tubular sections, the outer one 55 of which is the largest and is fixed on carriage 15. The others are movable sections 45, 35 and 25 which are adapted to roll or slide telescopically within each other and to reach their most contracted position within fixed member 55. The interconnection of the sections is such that if any one of them is urged in such direction as to contract the arm assembly, each section will move an equal distance concurrently, after which they will all come to rest in their home nesting position within fixed section 55. All movable sections also move equal distances concurrently when the arm assembly is extended.

The various telescoping arm sections, in this example, are steel tubes of square cross-section. They may be adapted to glide within each other by any suitable means such as on rollers. In this embodiment, the largest movable section 45 has steel blocks 27, 28, and 29 welded to it. Each block has a shaft on which there is journaled a ball bearing or roller 30. If section 45 is withdrawn from fixed section 55, roller 30 and the rollers that are carried on blocks 28 and 29, will roll on the internal surface of both section 55 and a bearing surface created by an angle rail 31 which is welded to the interior of section 55. It will be seen that the rollers on supporting blocks 27 and 28 accept the vertical stress due to the cantilever loading imposed by the X-ray tube casing and collimator while the other guide rail associated with block 29 guides and stabilizes the telescoping assembly against lateral loads. It will be seen by inspection of FIGURE 2 that the sections 25 and 35 are also provided with corresponding pairs of rollers that rotate on horizontal axes and another roller on a vertical axis which cooperates with guide tracks that are fixed on the next largest section for the purpose of supporting and guiding each section with respect to the other. Each guide rail like 31, is almost coextensive in length with the telescoping section to which it is attached. In FIGURE 3, the guide rollers and rails are omitted to facilitate explanation and eliminate the obscurity that would result from superposition of the parts in the drawing.

As stated earlier, the various telescoping sections 25, 35, and 45 are adapted to move in unison and equidistantly when a force is applied to any one of them for the purpose of contracting or extending the tube support arm 16. To achieve this end, the various sections are interconnected with chain and rack and pinion drives. Section 35 carries a shaft 33 which is journaled in a bearing 34 that is fixed on section 35. Shaft 33 is provided at one end with a sprocket 36 over which a closed loop of chain 37 runs. As seen in FIGURE 3, sprocket 36 has a mating idler sprocket 39 which is also journaled in a bearing like 34 that is fixed in section 35 and near the outside end thereof. The chain loop 37 is closed by anchoring its ends to a fixed block 40 on the smallest central section 25. Also on shaft 33 is a pinion 41 that engages with a gear rack 42 that is fixed on the inside of section 45 by screws or other suitable means.

The driving interconnection between the other sections is similar. To elaborate, the section 45 supports a bearing 43 in which a shaft 44 is journaled. At one end of the shaft there is a sprocket 46 with a chain 47 running over it, the free ends of the chain being connected to a block 48 that is carried by movable section 35. Shaft 44 also carries a pinion 49 that coacts with a rack 50, the latter being permanently attached to the interior of fixed section 55. The chain 47 also runs on an idle sprocket 51 which is journaled in a wall of section 45.

An understanding of how sections 25, 35, and 45 are compelled to move in unison when any one of them is urged axially, may be gained by focusing attention on

shaft 33 and its affiliated parts. In reference to FIGURE 2, assume that a force is applied to central section 25 such as to withdraw it lengthwise from the plane of the paper. Upon this event, chain 37 will translate and it will cause sprocket 36 to rotate. Were it not for shaft 33, no relative movement would take place between sections 25 and 35. However, pinion 41 on shaft 33, as a result of its interaction with rack 42, causes shaft 33 to translate and urge section 35 in the same direction as section 25 is moving.

Attention is now focused on shaft 44 and its associated parts to discover how section 45 is moved. When section 35 commences movement, it carries with it chain anchor block 48 which causes chain 47 to translate and rotate sprocket 46, which rotates with shaft 44 and pinion 49. The interaction between pinion 49 and stationary rack 50 on fixed section 55 then causes section 45 to translate at the same rate and distance as sections 25 and 35.

A concomitant of the telescoping section 25, 35, and 45 moving equal distances and in unison when one of them is moved, is that the locking of any one of the sections locks the others against relative movement with respect to each other. Thus, only a single lock is required in the instant design as compared with prior art telescoping supports in which each section must be locked individually. In the instant case, an electromagnetic lock is used. It consists of a stator housing 60 which has an internal winding, not shown, that produces a magnetic field when energized. Extending through housing 60 is a shaft 61 that carries at its lower end a brake disc 62 which is attractable into frictional engagement with the stator frame 60 when energized. This stops rotation of shaft 61. At the top end of shaft 61, as viewed in FIGURE 2, there is attached a sprocket 63 over which a chain 64 runs. The ends of the chain are connected with an anchor block 66 that is fixed on and moves with telescoping section 45. When the brake is deenergized, movement of the telescoping sections merely translates the chain and causes shaft 61 to rotate freely. When the brake is energized, disc 62 adheres and prevents rotation of shaft 61 which in turn prohibits chain 63 from translating and causes holding of section 45. By virtue of the interconnecting driving mechanism described above, the holding force is transmitted to the various sections and they are all prevented from moving.

How the telescoping assembly may be motorized should now be apparent. It is only necessary to substitute a motor for the brake assembly 60 in which case shaft 61 may be turned bi-directionally for transmitting a driving force through a chain like 64. If a brake and motorized assembly are both used, the motor unit may be mounted on the side of the outside section 55 as viewed in FIGURE 2. Because the outside fixed section 55 is fixed and extends through the front of vertical carriage 15, a drive motor may be located similarly to the brake assembly 60 in the back of the vertical carriage so that it is not seen from the front. It may also be remarked, incidentally, that necessary clearance between the wall of the room and the tubestand is held to a minimum by reason of the telescoping sections not extending backwardly beyond columns 10, 11 when the sections are retracted.

An important feature of the invention resides in the manner in which the upright 9 is maintained in true vertical attitude when it is being translated along guide tracks 12, 13. By reference to FIGURE 4, one may see that columns 10 and 11 are joined at their lower ends by a connecting member 70 which is equipped with wheels 71 that run on a floor mounted track 13. The upper ends of columns 10 and 11 are joined by a member 73 having characteristics similar to member 70 at the bottom. There is a pair of grooved pulleys 74 and 75 on bottom member 70. Another pair of pulleys 76 and 77 are journaled for rotation on the top member 73. A stabilizing cable 78 originates at an anchor point 79, at a suitable place on track 13, and runs over pulleys 75, upward of

column 11 and over pulley 77 to a point 80 where the cable is anchored to upper guide track 12. Another cable 81 originates at an anchor point 82 on the bottom track and it runs over lower pulley 74, up to column 10, whereupon it passes over pulley 76 and crosses over the other cable 78 and continues to an anchor point 83 on the upper track.

Thus, if there were a tendency for upright 9 to rotate clockwise as viewed in FIGURE 4, cable 78 would be placed in tension so as to prevent such movement. Conversely, cable 81 is placed in tension if there is a tendency for the columns to rotate counterclockwise. Consequently, no matter where a force is applied to upright 9 that would tend to cause it to translate along the upper and lower tracks, there will be no rotational movement and the upright will remain perfectly vertical. This eliminates any possibility of skewing and binding of the upright when it is being translated.

Because of the stabilizing influence of cables 78 and 81, it is possible to have wheels 71 close to each other rather than to have them spaced apart on a wide foot as is required in prior art room mounted tubestands. Hence, it is possible to move the tubestand over the entire length of the X-ray table 14 on a track that is about the length of the table. This facilitates installing the tubestand in a smaller room than was heretofore possible.

How the upright 9 is adapted to run on rails may be seen in FIGURE 6. Here it will be seen that there are a pair of lateral restraint rollers 84 that are in compressive relation with opposite sides of the upstanding portion of floor track 13 so as to prevent column 11 from moving away from the wall. There is also a roller 71 that bears the vertical thrust of the tubestand column.

It is easy to counterweight the vertical X-ray tube carriage 15 as may be seen in the schematic diagram in FIGURE 5. A counterweight 85 is arranged for vertical movement in an enclosure 86. The counterweight is suspended on a cable 87 which has one end fixed at 88 and another end fixed at 89. The vertical carriage 15 is suspended on cable 87 in balanced opposition to the tension imposed by counterweight 85 by means of a pair of grooved pulleys 90, 91 which are journaled on the back of the carriage for rotation. At the top of the vertical column there are provided rotatable pulleys 92 and 93 over which the cable runs in opposite directions in parallel with the guide track. One part of the cable 87 runs over a fixed pulley 94 on its way to the counterweight suspension pulley 95. Thus, it is seen that when the upright 9 is translated, vertical carriage 15 will remain at the same level since there will be no change in the length of the cable between pulleys 92 and 90, for example. Rather, cable 87 will pay out from one end and take up on the other end. An advantage of this arrangement is that the counterweight 85 need not be carried by the vertical columns and thereby impose additional load when the tubestand is moved. If the vertical carriage 15 is moved up or down, counterweight 85 moves in an opposite direction through a distance that is in the ratio of one-to-one.

In summary, there has been described an X-ray tube stand that is adapted for being located immediately next to the wall of a room away from the X-ray table itself. The tubestand offers a minimum of interference to movements of the operator about the table. The stand is provided with a telescoping arm that allows frontal and lateral aiming of the X-ray beam with respect to the patient when the table is in any attainable position without requiring the upright to be rotated or the arm to be swung during lateral radiography. The arrangement is such as to allow the guide tracks of the tubestand to be shorter than usual. The X-ray tube carriage can be moved entirely out of the way when it is not in use. The telescoping support also features unitary movement of its sections so as to facilitate their being interlocked or motor driven by a single braking or driving element. In

addition, the size of the tubestand is reduced and its stability improved through the use of criss-cross cables which maintain its vertical alignment during translation.

Although a preferred embodiment of the invention has been described, such description is to be considered illustrative rather than limiting, for the invention may be variously embodied and is to be limited only by the terms and scope of the claims which follow.

It is claimed:

1. An X-ray tubestand comprising:
  - an upright member having guide roller means at its upper and lower ends,
  - upper and lower horizontal tracks with which the rollers cooperate to allow translation of the upright member lengthwise of an X-ray table,
  - a carriage that is mounted on the upright member for bi-directional vertical movement thereon,
  - an extensible and contractible X-ray tube support extending in cantilever fashion from the carriage,
  - an X-ray tube casing that is carried by the support for being moved across the width of the X-ray table, said casing being mounted for rotation about its axis at an end of the support that is remote from the carriage,
  - first and second pairs of pulleys, with each being rotatably mounted near opposite ends of the upright member in substantial vertical alignment with the other pulley in a pair,
  - a pair of tense cables, each of which runs along the upright member and over each pulley in a pair and then substantially horizontal and opposite directions from each pulley toward fixed terminal points that are substantially on the level of the upper and lower guide track means, respectively.
2. A multiple section telescoping member, for supporting an X-ray tube, in which the sections move in unison when any one of them is moved, comprising:
  - a fixed section and a plurality of tubular movable sections of progressively smaller size so that the movable sections may slide within each other and the fixed section in a common axial direction,
  - a shaft that is journaled for rotation through the wall of each section that is intermediate in size as compared with any two sections that are inside and outside of the intermediate section and which shaft has a pinion on one end and a sprocket on the other,
  - a rack that is fixed inside one section, that extends in the direction of axis of the section, and that is engaged with the pinion, and
  - a closed loop of chain that runs over the sprocket and has its ends attached to another section,
  - whereby application of a force in the axial direction of a movable section will simultaneously impose a force on the other sections to drive them in unison.
3. An X-ray tube support comprising:
  - a movable carriage,
  - an axially immovable outer tubular section projecting from the carriage,
  - a plurality of tubular sections of progressively smaller size that are adapted to slide within each other and the outer section in a common axial direction,
  - a shaft that is journaled for rotation through the wall of the first section that is the next innermost section from the fixed section,
  - the said shaft having a sprocket on one end and a pinion on the other,
  - a gear rack fixed on the interior of the immovable outer section and engaged with the pinion, said gear rack being disposed in the axial direction of the sections,
  - a chain which has its ends fixed to the second next innermost section from the outer section and which runs over the sprocket,

- (h) another shaft journaled for rotation through the wall of the second next innermost section,
  - (i) said other shaft having a sprocket on one end and a pinion on the other end,
  - (j) a gear rack fixed on the interior of the first innermost section and engaged with the pinion on the other shaft, said gear rack being disposed in the axial direction of the sections,
  - (k) a second chain which has its end affixed to the third innermost movable section and which runs on the sprocket of the second shaft,
  - (l) whereby an axial force applied to any movable section effects an interchange or rotational and translational forces for moving all movable sections equidistantly and in unison, and,
  - (m) an X-ray tube casing mounted at an end of the most innermost movable section that is remote from the carriage.
4. The invention set forth in claim 2 including brake means for holding all movable sections by applying a braking force to one of them, said brake means comprising:
- (a) a fixedly mounted electromagnetic element, and
  - (b) means for effecting an attractive coupling between said one movable section and said electromagnetic member when the latter is energized.
5. The invention set forth in claim 3 including a single brake means for holding the movable sections against axial movement, said brake means comprising:
- (a) an electromagnetic member that is mounted on the outermost fixed tubular section, and
  - (b) means for effecting an attractive coupling between a movable section and said electromagnetic element when the latter is energized.
6. The invention set forth in claim 3 including an electromagnetic brake for holding all sections against axial movement by holding one of them, comprising:
- (a) an electromagnetic stator mounted on the outermost fixed tubular section,
  - (b) a shaft projecting through the stator and having a brake disk at its one end and a sprocket on the other,
  - (c) an idler sprocket journaled for rotation on the fixed tubular section, and
  - (d) a chain that runs over said sprockets and whose ends are attached to the tubular section that is next innermost from the fixed section,
  - (e) whereby attraction of said disk by energization of the electromagnet will hold all sections that are

5

10

15

20

25

30

35

40

- coupled together.
7. An X-ray tube support comprising:
- (a) an axially immovable tubular member,
  - (b) an outermost movable tubular member next inside the immovable member,
  - (c) an intermediate movable tubular member inside the outermost movable tubular member,
  - (d) an inner movable tubular member inside the intermediate tubular member,
  - (e) all of said movable members being movable with respect to each other and with respect to the immovable member in the direction of their common axis,
  - (f) individual shafts journaled for rotation in and extending through the outermost movable member and the intermediate member, respectively, the said shafts having their axes in a plane that is substantially at right angles to the common axis of the members,
  - (g) toothed means at each end of each shaft,
  - (h) tooth engaging means that are carried by the outside of the inner and intermediate members, and by the inside of the immovable and the outermost movable member, which tooth engaging means are engaged respectively with the toothed means to rotate the same when any of the tubular members is moved axially.
